US0D1019715S

(12) **United States Design Patent** (10) **Patent No.:** **US D1,019,715 S**
(45) **Date of Patent:** **** Mar. 26, 2024**

(54) **POD FOR INDOOR PLANT CULTIVATOR**

(71) Applicant: **LG ELECTRONICS INC.**, Seoul (KR)

(72) Inventors: **Minsub Kim**, Seoul (KR); **Kyukwan Choi**, Seoul (KR); **Yong Kim**, Seoul (KR)

(73) Assignee: **LG ELECTRONICS INC.**, Seoul (KR)

(**) Term: **15 Years**

(21) Appl. No.: **29/819,151**

(22) Filed: **Dec. 13, 2021**

(51) LOC (14) Cl. **15-07**

(52) U.S. Cl. **USPC D15/89**

(58) **Field of Classification Search**

(57) **CLAIM**

The ornamental design for a pod for indoor plant cultivator, as shown and described.

DESCRIPTION

FIG. 1 is a front perspective view of the pod for indoor plant cultivator showing our new design;

FIG. 2 is a front view thereof where the back view is a mirror image;

FIG. 3 is a left side view thereof where the right side view is a mirror image;

FIG. 4 is a top plan view thereof;

FIG. 5 is a bottom plan view thereof;

FIG. 6 is a bottom perspective view thereof;

FIG. 7 is an exploded view; and,

FIG. 8 is a perspective view showing the state of use that the claimed design is being installed at the inside of indoor plant cultivator after placing on the shelf for indoor plant cultivator.

The portions of FIG. 7 drawn in broken lines depict portions of the pod for indoor plant cultivator that form no part of the claimed design. The portions of FIG. 8 drawn in broken lines show environmental structure only and form no part of the claimed design.

1 Claim, 8 Drawing Sheets
